UNITED STATES PATENT OFFICE.

GEORGE M. CONWAY, OF MILWAUKEE, WISCONSIN.

CUT-OFF-VALVE GEAR.

SPECIFICATION forming part of Letters Patent No. 269,265, dated December 19, 1882.

Application filed December 13, 1881. (No model.)

To all whom it may concern:

Be it known that I, GEORGE M. CONWAY, of Milwaukee, in the county of Milwaukee, and in the State of Wisconsin, have invented certain new and useful Improvements in Automatic Cut-Off-Valve Gear for Steam-Engines; and I do hereby declare that the following is a full, clear, and exact description thereof.

My invention relates to automatic-cut-off steam-engines, and will be fully described hereinafter.

In the drawings, Figure 1 is a side view of my improved engine. Fig. 2 is a detail. Fig. 3 is a top view, and Figs. 4 and 5 are details.

A is the steam-chest, and B B are two valve-chambers containing each a gridiron-valve, *a*. *b b'* are the valve-rods, each of which has an enlargement, *b''*, that serves as a piston. After passing through the bottom of the valve-chest the rods *b b'*, extending nearly to the bed-frame of the engine, are provided there with air-caps *g*, that fit upon stationary heads *g'*. This part of my invention will be more fully described farther on. The upper end of the rod *b* is provided with a trip-ferrule, *c*, and the rod *b'* with a similar one, *c'*. In ferrule *c* is pivoted a trip, *d*, and in ferrule *c'* a trip, *d'*. The trips *d* and *d'* are precisely alike, and a description of one will answer for both, and therefore I will refer to trip *d*. (Shown in detail to the left of Fig. 1.) The trip *d* consists of an upright portion recessed in front to receive a hard-metal plate, *e*, and beneath it a cushion, *f*. The plate *e* projects beyond the cushion *f* to receive a plate, *m*, on the top, and cushion *f* receives the end of beam *H*. On the lower end of the trip *d* is a rounded shoulder, *h*, through which the bolt by which it is pivoted to the ferrule *c* passes, and this bolt is directly on a line with the plate *e*.

Projecting from trip *d*, and just back of shoulder *h*, is an arm, *i*, and a spring, *j*, secured to ferrule *c*, bears upon the under side of arm *i* to throw the trip forward against the end of beam *H*. A post, *D*, just behind trip *d*, carries another trip, *M*, that has an arm, *N*, projecting over arm *i* of trip *d*, and trip *M* is connected to one end of a lever, *F*, on rock-shaft *G* by a rod, *E*, and the other end of this lever is connected by a rod, *E'*, to a trip, *M'*. The rock-shaft *F'* is bracketed to the governor-stand *G*, and its arm *P* is pivoted to the slide

of the governor-stem; (not shown,) so that when the slide is raised by the arms of the governor as they are thrown out by an increase in the velocity of their revolution the arm *P* of the rock-shaft will be drawn up, causing lever *F* to pull rod *E* and thrust rod *E'*. The beam *H* is trunnioned to the steam-chest midway between posts *D* and *D'*, and, when horizontal, projects on each side sufficiently far to touch each of the cushions *f* of the trips *d* and *d'* when said trips are in a vertical position, as shown. Fig. 1 of the drawings shows the position of the parts of my engine when the eccentric on the driving-shaft (not shown) is at half-travel. Both valves are barely closed, and their rods are suspended each from one end of the beam *H*. Now, as the eccentric continues on toward the completion of its travel its rod *K'*, thrusting upon the arm *K* of beam *H*, will cause it to dip one end, *m'*, and elevate the other, *m*, and the latter will carry the trip *d* up with it until its arm *i* strikes the arm *N* of trip *M* and trips it out of engagement with the beam. Instantly upon the trip *d* being released by the beam *H* its rod *b* will be drawn down by steam-pressure on the piston *b''* of rod *b* to close the valve *a*. The other end of beam *H* acts in precisely the same way upon trip *d'* and valve-rod *b'*.

It will be seen that the lever *F* is exactly vertical. This is its position when the engine is at its normal speed and the trips *M M'* are in position to limit the period between the pulsations of the valves to just the work needed; but should the supply of steam decrease, or should additional machinery be belted to the engine, then just as soon as the driving-shaft begins to slow up the balls of the governor, falling, will throw the lever *F* out of a perpendicular and cause its rods to tilt the trips *M M'* away from trips *d d'*, so as to permit the rods *b b'* to be carried higher by the beam before the tripping takes place. When the engine is at rest the governor-arms hang down toward a vertical position, and the rods *E E'* hold the arms *M M'* entirely out of the way of trips *d d'*, so that when the ends of beam *H* rise and fall they carry the trips with it both ways, alternately opening and closing the valves *a* and holding each open as long as the driving-piston is going from it, and this continues until the governor-arms leave the stand

and begin to draw upon the arm of rock-shaft F'. This immediately throws the lever F into a perpendicular and causes its rods E E' to throw the trips M M' into position to throw 5 trips d d' out of contact with beam H and shorten the stroke of valve-rods b b' sufficiently to cut off steam so rapidly that only sufficient will be permitted to enter the cylinder at each pulsation to propel the piston from one end to 10 the other and keep up its motion, and thus any increase or decrease in the speed of the governor be corrected by cutting off steam earlier or later in the stroke of the engine, according to the requirements of the work to be done by 15 the engine, keeping the speed always uniform.

In fact I have by actual test found that the variation in the motion of my engine is not more than half of one per cent. between the two extremes of running the friction of the 20 engine and of carrying her full load, or between the lowest pressure at which steam can be cut off and keep up the motion and running up to one hundred pounds pressure—a result never before attained, to my knowledge, previous to 25 this my invention.

To guard against the mischief that might result from the breaking of the belt or gearing that communicates motion from the driving-shaft to the governor-stem, I attach a sprocket-wheel, s, to each of trips M and M' and another to each of trips d d', and these I connect by a chain. These wheels slide upon their pivots, and are locked by pins or any other suitable means. After the engine has attained her regular speed and the trips are in the position in 35 Fig. 1, I turn the wheels and tighten the chain. It will now be utterly impossible for the engine to run away, even if the governor-stem should become disconnected from the driving-power and the governor-arms should fall, for 40 their falling, instead of relieving the trips d d', will cause the trips M M' to draw them entirely out of contact with the beam H, so that its oscillations will not raise the valve-rods to admit 45 steam to the cylinder. Of course the chain must have slack enough to permit the regular action of the trips when the governor-arms are revolving.

Each air-cushion consists of a cap, g, secured to the lower end of its valve-rod, and having an annular depression, h', in its top, and grooves o in its lower portion or rim. This cap fits over a stationary head, g', that is cast with a central screw-threaded cylinder, h'', to receive the screw-threaded bushing l of 50 a needle-valve, l'. On its top the head g' has a circular projection that fits in the depression h', and an aperture, n', serves to permit the escape of air to the cylinder h'', from whence 55 it escapes to an annular chamber between the cylinder h'' and the walls of head g'. This escape of air is regulated by the needle-valve l'. I secure a packing-ring about the head g', and below it reduce the head slightly. As the 60 valve-rod is raised it carries the cap g with it, air entering at first through perforations n to prevent the formation of a vacuum in the cap

until the cap has raised sufficiently to carry the grooves o in its sides high enough to open into the space between the cap and the head, 70 and above the packing-ring. On returning the cap meets with very slight resistance until the grooves o have passed below the packing-ring. After this occurs the only outlet for the air is through perforation n', and by means of 75 the needle-valve l' the size of this exit may be regulated to the greatest nicety, so that while the resistance in the cup may not be great enough to prevent the valve a from closing it will be a perfect cushion for the rod, 80 and as the air makes its exit from the cylinder h'' into the annulus about the cylinder the sound produced by the rush of air is deadened.

I l' are the rods of exhaust-valves S S', and are connected by a bar, u, with each other and 85 the arm K, so that a forward stroke of arm K, that will close exhaust-valve S and open valve S', will cause the beam H to open valve a, and a backward stroke of arm K, that will open valve S and close S', will at the same 90 time close valve a and lift rod b' to open its valve.

Having thus described my invention, what I claim as new, and desire to secure by Letters Patent, is—

1. The beam H, pivoted between the upper ends of the valve rods, in combination with trips—one on each valve-rod—adapted each to engage with one end of the beam, and other trips connected with the governor-stem and 100 engaging with the first-named trips, as set forth.

2. The combination of trips d d' and M M', connected by chains or cords, and a winding device, with rods E E', connecting them with 105 the governor-stem, as set forth.

3. The valve-rods having enlargements b'' for receiving the returning impact of the steam, and having caps g on their lower ends, in combination with stationary heads, each head having a central cylinder, h'', apertured to permit the escape of air through it from between the cap and head into an annulus about it, (the said cylinder,) as set forth.

4. Cap g, the wall of which is grooved on 115 its inside vertically, in combination with the head having its wall reduced on its outside, and having a packing-ring about it just above its reduced portion, as set forth.

5. The cap g, in combination with head g', 120 having a central cylinder, h, with apertures leading from between the head and its cap into an annular chamber between the cylinder and the outer wall of the head for deadening the sound occasioned by the expulsion 125 of the air, as set forth.

In testimony that I claim the foregoing I have hereunto set my hand this 7th day of November, 1881.

GEO. M. CONWAY.
